UNITED STATES PATENT OFFICE.

RALPH S. BAUER, OF LYNN, MASSACHUSETTS.

DESIGN FOR A CASING FOR MECHANICAL TOYS.

No. 39,776.

Specification for Design.

Patented Jan. 19, 1909.

Application filed October 2, 1908. Serial No. 455,927. Term of patent 14 years.

To all whom it may concern:

Be it known that I, RALPH S. BAUER, a citizen of the United States, residing at Lynn, in the county of Essex and State of Massachusetts, have invented a new, original, and ornamental Design for a Casing for a Mechanical Toy, of which the following is a specification, reference being had to the accompanying drawing, forming part thereof.

Figure 1 is a front elevation of a casing for a mechanical toy. Fig. 2 is a side ele-

vation of a casing for a mechanical toy. Fig. 3 is a rear elevation of a casing for a mechanical toy.

I claim:

The ornamental design for a casing for a mechanical toy, as shown.
